[57] **ABSTRACT**

The panel type wall comprises a plurality of panels disposed side by side and further comprises ties in the rear of the panels for interconnecting the next adjacent panels in a manner in which the confronting edges are in abutting relationship with one another. These ties can be rendered ineffective by moving one of the panels relative to others so that the one panel can be removed from the panel wall.

PANEL TYPE WALL HAVING TIES FOR INTERCONNECTING THE PANELS

BACKGROUND OF THE INVENTION

1. Field of the Invention

The field relates to panel type walls employing ties between the confronting edges of adjacent panels, such being classified principally in Classes 52 and 189.

2. Description of the Prior Art

A search of the prior art revealed the following patents:

PAT. NO.	Patentee	Issue Date
955,103	Plym	April 12, 1910
1,752,002	Isgur	March 25, 1930

3,429,090	Metelnick	February 25, 1969

None of these patents disclose a panel wall having tie elements disposed in the rear of the panels and none are designed so that the confronting edges of adjacent panels are in abutting relationship.

SUMMARY OF THE INVENTION

The rear side of each panel is provided with an elongated groove. A plate is fixed to the rear side of each panel, each plate including aligned longitudinally extending slots that are aligned with the groove in the panel. A strip is provided having aligned longitudinally extending hooks that are arranged to extend through the slots; and by shifting the strip, the hooks slide into latching position with the fixed plate. The strips of the next adjacent panels have sections that extend between resilient and flexible tines on a panel supporting frame, and when so extended, the panels are pulled toward one another to positions in which the confronting edges of the panels are in abutting relationship.

Other features and the advantages of the present invention will be apparent from the following description, reference being made to the accompanying drawings wherein a preferred embodiment of the invention is illustrated.

BRIEF DESCRIPTION OF THE DRAWINGS

FIG. 1 is a fragmentary view showing fronts of fragments of two panels, also showing fragments of the elements which hold the edges of the panels in abutting relationship;

FIG. 2 is a fragmentary view of a strip having aligned hooks, the view looking in the direction of arrows 2-2 of FIG. 1;

FIG. 3 is a fragmentary sectional view taken along line 3-3 of FIG. 1;

FIG. 4 is a fragmentary sectional view taken along line 4-4 of FIG. 3; and

FIG. 5 is a front view of two adjoining panels and fragments of two additional panels being shown.

DESCRIPTION OF THE PREFERRED EMBODIMENT

Referring first to FIG. 5, a fragmentary front view of a panel wall 10 is shown, the fragment including two wallboard type panels 12 and 14 and two adjoining like panels 16 and 18. Referring now to the remaining FIGS., panel 12 is provided with a longitudinal groove 20 which lies adjacent and parallel with an edge 22 of that panel. Likewise, panel 14 is provided with a groove 24 which lies adjacent and parallel with an edge 26 of panel 14.

Plate means in the form of a single, elongated plate 28 is fixed in any suitable manner, as by glue, to the rear side of panel 12. This plate is provided with a plurality of elongated slots 30. These slots extend parallelly with the groove 20 in panel 12 and register with the groove 20. Likewise, plate means in the form of a single, elongated plate 32 is fixed to the rear side of panel 14. Plate 32 is provided with a plurality of elongated slots 34. These slots 34 extend parallelly with the groove 24 in panel 14 and register with the groove 24.

Strip means in the form of a single elongated strip 36 is provided with a plurality of aligned and longitudinally extending hooks 38. These hooks are adapted to extend longitudinally through the slots in plate 28 and into groove 20 in panel 12. This is more clearly shown in FIG. 4 wherein a strip means in the form of a single strip 40 is also provided with a plurality of aligned and longitudinally extending hooks 42. Hooks 42 are adapted to extend through plate 32 and into the groove 24 of panel 14. By sliding the plate 32 to its extreme right position, which position is shown in FIG. 4, the hooks 42 frictionally engage the inside surfaces of the plate 32. Likewise, the hooks 38 of strip 36 are adapted to engage the inside surfaces of plate 28. Thus the strips 36 and 40 are frictionally held in position with respect to the plates 28 and 32, yet they can be shifted manually so that they can clear the slots in the plates.

The strip 36 has a section 44 which abuts the rear side of plate 28. This section extends toward the edge 22 in panel 12. It also has a section 46 which extends rearwardly. Strip 40 also has a section 48 which abuts the rear side of plate 32 and it extends toward the edge 26 of panel 14. Strip 40 is also provided with a section 50 which extends rearwardly.

A frame comprises a plurality of joined wires 52, preferably formed of steel, which extend longitudinally and are aligned, in the present disclosure, in superimposed relationship. Each of the joined wires 52 is provided with tine sections 54, 56, 58 and 60. The tine sections 54 and 56 are adapted to receive the rearwardly extending sections 46 and 50 of strips 36 and 40, respectively, and the tine sections 58 and 60 are adapted to receive like rearwardly extending sections that are incorporated in panels like panels 12 and 14. Either the tine sections of the wire frames or the sections of the strips 36 and 40 may be formed of resilient and flexible metal, for example steel. As herein shown, the tine sections are formed of resilient and flexible material whereby, when the rear sections 46 and 50 are pushed between the tine sections 54 and 56, the edges 22 and 26 of panels 12 and 14 are pulled into abutting relationship. Thus only a crack is visible between adjacent panels.

When assembling two panels, such as panels 12 and 14, the strip 36 is attached to the panel 12 by inserting the hooks 38 of that strip through the slots 30 in plate 28. Then the strip is shifted manually so that it frictionally engages the inner surfaces of the plate. The same action is applied for attaching the strip 40 to plate 32 on the panel 14. The panels can be pushed rearwardly independently or in unison whereby the strip sections 46 and 50 are frictionally held in place by the tines 54 and 56. To remove a panel, for example panel 14, from a panel type wall such as wall 10, panel 14 is raised sufficiently, while the strip 36 is held in position by tine sections 54 and 56, so that the slots 34 are moved in positions at which the hooks no longer retain the plate 32. Then by pulling forwardly on the panel 14, it can be removed from adjacent panels 12 and 18.

Thus it is apparent from the foregoing that by virtue of the present invention, I have provided a panel type wall in which the confronting edges of adjacent panels are in abutting relationship, yet the interconnecting means is not visible. Also, I have provided for the ready assembling of a plurality of separate panels and the ready removal of a panel which is interposed between adjacent panels.

Having described my invention, I claim:

1. A panel type wall comprising in combination:
- A. a frame for supporting panels, said frame including sections confronting one another;
- B. a panel, said panel being grooved adjacent an edge thereof;
- C. plate means fixed to the panel, said plate means lying parallelly with the panel and having a plurality of longitudinally extending slots therein in registry with the groove in said panel;
- D. a second panel having an edge adjoining said edge of the first mentioned panel, said second mentioned panel being grooved adjacent the said edge

thereof;

E. second plate means fixed to the second mentioned panel, said latter means lying parallelly with the second mentioned panel and having a plurality of longitudinally extending slots therein in registry with the groove in the second mentioned panel;

F. strip means having:

1. a plurality of longitudinally extending and aligned hooks, said hooks extending through the slots of the first mentioned plate means, said strip means being slidable longitudinally for hooking the hooks thereof against the rear side of the first mentioned plate means;

2. a section extending between the confronting sections of the frame, certain of said sections being flexible and resilient for yieldingly holding the strip means in position;

G. second strip means having:

1. a plurality of longitudinally aligned hooks, said hooks extending through the slots of the second mentioned plate means, said latter strip means being slidable longitudinally for hooking the hooks thereof against the rear side of second mentioned plate means;

2. a section extending between the confronting sections of the frame, certain of the sections being flexible and resilient for yieldingly holding said second mentioned strip means in position.

2. A panel type wall as defined in claim 1, characterized in that the sections of the frame are flexible and resilient.

3. A panel type wall as defined in claim 1, characterized in that the edges of the panels are in abutting relationship.

35 4. A panel type wall as defined in claim 1, characterized in that the width of the slots is greater than the thickness of the hooks.
